Patented Oct. 14, 1975

237,139

PORTABLE DESOLDERING TOOL OR THE LIKE

William S. Fortune, 14250 Dearborn St.,
Panorama City, Calif. 91402

Filed Aug. 17, 1973, Ser. No. 389,382

Term of patent 14 years

Int. Cl. D8—05

U.S. Cl. D8—30

Fig. 2

Fig. 3

Fig. 4

Fig. 5

FIG. 1 is a side elevational view of a portable desoldering tool or the like embodying my new design;

FIG. 2 is a bottom view thereof;

FIG. 3 is a plan view thereof;

FIG. 4 is a side elevational view thereof illustrating the tool with elements in an alternate position.

FIG. 5 is a rear, end elevational view thereof.

I claim:

The ornamental design for a portable desoldering tool or the like, substantially as shown and described.
